Primary Examiner — John R Yeh(57) **CLAIM**

The ornamental design for a portable clothes dryer, as shown and described.

DESCRIPTION

FIG. 1 is a top, front and right side perspective view of a portable clothes dryer, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view showing the portable clothes dryer with the bottom cover removed, connected with its storage bag, and with the hook in a open state;

FIG. 10 is another perspective view thereof; and,

FIG. 11 is an enlarged view of portion 11 in FIG. 10.

The dash-dash broken lines in the figures illustrate environment of the portable clothes dryer and form no part of the claimed design. The dot-dash broken lines depict enlargement indications that form no part of the claimed design.
